UNITED STATES PATENT OFFICE.

ALEXANDER NYMAN, OF WILKINSBURG, PENNSYLVANIA, ASSIGNOR TO WESTINGHOUSE ELECTRIC & MANUFACTURING COMPANY, A CORPORATION OF PENNSYLVANIA.

COMBINED WIRELESS SENDING AND RECEIVING SYSTEM.

Application filed July 15, 1920. Serial No. 396,533.

To all whom it may concern:

Be it known that I, **ALEXANDER NYMAN**, a citizen of the United States, and a resident of Wilkinsburg, in the county of Allegheny and State of Pennsylvania, have invented a new and useful Improvement in Combined Wireless Sending and Receiving Systems, of which the following is a specification.

My invention relates to systems for simultaneously sending and receiving messages on the same apparatus so that the same antenna may be used to both send and receive without necessitating switching.

More particularly, my invention relates to an apparatus for simultaneously sending and receiving radio messages, and to the use of a main antenna circuit having inductance, and a shunt circuit having inductance, the inductance of the main and shunt circuits neutralizing each other in their effect upon the receiving circuit when a message is sent but permitting received oscillations to be caught.

It has been difficult to both send and receive at the same time, where communications were being transmitted and received from the same station, for the reason that the waves sent from the home station are tuned to the length of those received and the receiving apparatus responded to both. It has not been possible to successfully send and receive simultaneously under the above outlined conditions.

This invention is conceived with the idea of rendering feasible the simultaneous use of a wireless apparatus both as a sending and as a receiving station, and, at the same time, to accomplish that result while using the same antenna.

An object of my invention is to provide means for sending and receiving wireless messages without necessitating any switching operations.

With these and other objects in view, which may be incident to the improvements, my invention consists in the parts and combinations to be hereinafter set forth and claimed, with the understanding that the several elements comprising my invention may be varied in their proportions and arrangement without departing from the spirit and scope of the appended claims.

In order to make my invention more

clearly understood, I have shown, in the accompanying drawings, means for carrying it into practical effect without limiting the improvements, in their useful applications, to the particular constructions, which, for the purpose of explanation, have been made the subject of illustration.

In the accompanying drawings, Figure 1 is a diagrammatic view of a combination sending and receiving station constructed in accordance with the principles of my invention.

Fig. 2 is a diagrammatic view in which the dotted lines indicate the portion of my apparatus which acts as an operative part of the receiving station.

Fig. 3 is a diagrammatic view illustrating the flow of currents in the apparatus when it is used as a sending station.

Fig. 4 is a diagram illustrating the flow of currents through my apparatus when it is used as a receiving station.

Figs. 5 and 6 are diagrams illustrating different arrangements of apparatus that may be used within the spirit of my invention.

Referring to the drawings, I have shown an antenna 1 having a neutralizing inductance 2, a main inductance 3 of a variable quantity and a variable capacitance 4 through which the circuits are grounded. A shunt circuit is provided having a variable inductance 5, a variable capacitance 6 and a variable resistance 7. The shunt circuit above mentioned is tuned to approximately the same frequency as the main antenna circuit so that oscillations sent or received will pass through the shunt circuit. I have found, however, that it is not necessary to tune the shunt circuit exactly to the main-antenna-circuit frequency. The variable resistance 7 is adjusted to limit the amount of wasted sending power expended through the shunt circuit.

In inductive relation to the inductance 3 of the main circuit is a variable inductance 8 through which power is delivered to the antenna circuit. The variable inductance 8 has a variable capacitance 9 connected in parallel with it so that the circuit may be readily tuned to any desired frequency. In circuit through the inductance 8 and the capacitance 9 is a filament element 10 and

a plate element 11 of an electron tube 10' having a grid element 13 connected to the inductance 8 to furnish the feed back between the grid and plate circuits necessary for sustained oscillations.

A suitable battery 14 provides current for heating the filament element 10. The arrangement is the customary one for using an electron tube as a generator of radio-frequency alternating current.

In circuit with the plate circuit of the electron tube 10' is a plate 15 and a filament 16 of an electron tube 17, acting as a modulator and having a grid element 18. The filament 16 is heated by means of a suitable battery 19.

Within the plate circuit of modulator tube 17 is an inductance 20. A "C" battery 22' is provided in circuit with the grid 18, the negative terminal of which applies its potential to the grid 18. Within the grid circuit is located an inductance 22.

Provided within the circuit of the two electron tubes 10' and 17 is a generator 21' having a high-reactance coil 22" that acts as a constant source of current and delivers power to the generator tube 10'.

Coupled inductively to the inductance 22 is an inductance 23 of a microphone circuit 30 that includes a battery 24 and a microphone 25. Variations of the microphone-circuit current by reason of the voice causes a variation in potential of the grid 18 of the modulator tube 17 because of the inductive coupling of the inductances 22 and 23 and thus, variation of potential of the grid 16 causes the tube 17 to absorb power in accordance with the change of potential.

Though I have shown a generator tube 40 coupled with a modulator as a generator of radio-frequency oscillations the amplitude of which is controlled by voice, any method of generating sending oscillations may be used, such as the Poulsen arc or the high-frequency generator, and it is to be understood that my invention is not limited to any particular type of apparatus for generating radio-frequency current but that the apparatus which I have shown is merely 50 for purposes of illustration.

In inductive relation to the neutralizing inductance 2 of the main antenna circuit and, likewise, to the inductance 5 of the shunt circuit, is an inductance 26 of the 55 receiving circuit. This inductance is so placed that, upon the sending of a message, the inductive effect of neutralizing inductance 2 and inductance 5 of the shunt circuit will balance and react to produce 60 a zero electromotive force within this coil. This phenomenon will be more fully explained in the paragraphs to follow.

In circuit with the inductance 26 is a 65 variable capacity 27 and a condenser 28. An electron tube 29, acting as a detector and

having a grid element 30, a plate element 31 and a filament element 32, is in circuit with the inductance 26.

In circuit across the condensers 27 and 70 28 is a resistance 33 that performs the function of the customary grid leak in the grid circuit of tubes acting as detectors.

To heat the filament 32, I provide an "A" 75 battery 34. The amount of current flowing through the filament 32 is controlled by the insertion of a variable resistance 34'. Within the plate circuit of the electron tube 29 are located telephone receivers 35, having a capacity 36 shunted between them. A suitable "B" battery 37 applies positive potential to the plate 31. There should be no mutual inductance, as will be apparent, between certain of the coils. To avoid this mutual inductance, these coils may be placed at right angles to each other. To avoid the effect of stray field upon the coils, they may be encased within metal containers or boxes. It is most necessary to the efficient operation of this system that the inductance be free from the effect of stray fields and that certain of the coils should not have mutual inductance between them, and any methods may be used to obtain these results, the above outlined methods being but two of many that may be employed.

90 Referring to Fig. 2, which is a diagrammatic illustration of the antenna circuits, the dotted lines surrounding a portion of the circuit indicate the effective part of the circuit when the apparatus is used as a receiving circuit. It will be noted that this effective receiving circuit includes the inductance 26, the neutralizing inductance 2 and the inductance 5 of the shunt circuit.

95 Fig. 3 denotes the direction of the currents 100 in the main and shunt circuits of the antenna when a message is being sent. Since the shunt circuit is tuned to the approximate frequency of the main circuit and is parallel thereto, the flow of current in the 110 two circuits is in opposite directions.

115 By reason of the fact that the neutralizing inductance 2 is a portion of the main antenna circuit, the flow of current in it is in a direction opposite to the flow of current in the inductance 5 of the shunt circuit.

120 By proper arrangement of the values and positions of these inductances, the effect upon the inductance 26 of the receiving circuit can be made zero since the currents are 125 opposite in phase.

In operation of the apparatus as a sending station, the tube 10' is arranged to act as a generator of radio-frequency current, there being mutual inductance between the 130 plate and grid circuits.

The capacity 9 is variable and, likewise, the inductance 8 may be made of variable quantity, so that the sent oscillations may be tuned to the desired frequency.

The tube 17 acts as a modulator of the radio frequency current generated by the tube 10'.

The microphone 25 causes oscillations of audio frequency in inductance 23 and this, in turn, induces oscillations of audio frequency in inductance 22.

Because of the change in grid potential of the grid 18, audio frequency oscillations are set up within the plate circuit of the modulator tube 17.

In accordance with the well known principles of radio transmission, the audio-frequency oscillations absorb power from the input of the antenna and these audio-frequency oscillations will affect the amplitude of the radio frequency oscillations sent out. This produces the audio pulses necessary for the transmission of a message.

Fig. 4 illustrates, diagrammatically, the flow of currents in the antenna circuit when the apparatus is receiving messages. The currents through the neutralizing inductance 2 of the main-antenna circuit and through the inductance 5 of the shunt circuit travel in the same direction, and the effect upon the inductance 26 of the receiving circuit is the arithmetical sum of the effects of the first mentioned inductances. Thus, oscillations are induced in the inductance 26. This induced current affects the potential of the grid 30, of the electron tube 29 and, as the proper conditions for use of this tube as a detector are present, oscillations are set up in the plate circuit corresponding to the received oscillations, and messages may be taken through the telephone receivers 35.

By virtue of adjustment of the variable capacity 27, the circuit may be tuned to any desired frequency. It is obvious that any method of detecting the received oscillations may be employed, and that I have shown an electron tube, used as a detector of radio frequency, solely for the purpose of illustration and to make clear the utility of my invention and its application to the problems of radio communication.

From the foregoing it will be apparent that, in the operation of receiving by reason of the direction of flow of current, the effect of the neutralizing inductance and the shunt circuit inductance upon the receiving inductance is the arithmetical sum of these two. However, in sending messages, since the currents traverse the neutralizing inductance 2 and the shunt circuit inductance 5 in opposite directions, the effect of each tends to neutralize the other in its action upon the receiving inductance, and, by proper adjustment of position of coils and of values, the inductive effect upon the receiving inductance may be made equal to zero when the apparatus is used as a sending station.

In Fig. 5 is shown a modification of the arrangement of circuits that may be em-

ployed. In this case, the variable inductance 5 of the shunt circuit is located between the neutralizing inductance 2 and the receiving inductance 26.

Another arrangement of apparatus that may be employed is shown in Fig. 6, in which the inductance 5 of the shunt circuit is shown as located between the neutralizing inductance 2 of the main circuit and the receiving inductance 26 of the receiving circuit. Conductively connected between the neutralizing inductance 2 and the inductance 5 of the shunt circuit, is located a variable inductance 40, that forms part of the antenna circuit. The operation of the modifications shown in Figs. 5 and 6 is similar to that previously described relative to the type shown in Figs. 1 to 4, inclusive; in sending, the shunt-circuit inductance and neutralizing inductance balance in their effects on the receiving inductance while, in receiving, their effects are added.

While I have described but three embodiments of my invention, it will be apparent to those skilled in the art that many modifications may be made therein without departing from the spirit of the invention and I desire, therefore, that my invention shall be limited only as set forth in the appended claims or by the showing of the prior art.

I claim as my invention:

1. The combination with a source of currents having an alternating-current component, of a translating device adapted to both supply and utilize currents having an alternating-current component, a main neutralizing reactance device, a main circuit including said source, said main neutralizing reactance device and said translating device, an auxiliary neutralizing reactance device, an energy-absorbing device, an auxiliary circuit including said source, said main and auxiliary neutralizing devices and said energy-absorbing device, and a receiving circuit coupled to both of said neutralizing devices.

2. The combination with a source of modulated radio-frequency currents, of a translating device adapted to both transmit and receive modulated radio-frequency currents, a main neutralizing reactance device, a tuned main circuit including said source, said main neutralizing reactance device and said translating device, an auxiliary neutralizing reactance device, an energy-absorbing device, a similarly tuned auxiliary circuit including said source, said main and auxiliary neutralizing devices and said energy-absorbing device, and a receiving circuit coupled to both of said neutralizing devices.

3. The combination with a source of modulated radio-frequency currents, of an antenna, a main neutralizing device, a tuned main circuit including said source, said main

neutralizing device and said antenna, an auxiliary neutralizing device comprising an energy absorbent means, an auxiliary circuit including said source, said main and auxiliary neutralizing devices and said energy-absorbing device, and a receiving circuit coupled to both of said neutralizing devices.

4. In a radio system, a divided antenna circuit having two branches, an inductor in each branch, a receiving circuit in inductive relation with said inductors, one of the branches of the antenna circuit including

an additional inductor adapted to be coupled to a sending apparatus, the portion of the 15 other of said branches of the antenna circuit external to the inductor therein being substantially free from inductance, and means associated with said additional inductor for impressing sending energy upon the 20 antenna circuit.

In testimony whereof, I have hereunto subscribed my name this 10th day of July 1920.

ALEXANDER NYMAN.
